UNITED STATES PATENT OFFICE.

THEODORE R. HOFFMAN, OF CLEVELAND, OHIO.

PAPER-FASTENER.

SPECIFICATION forming part of Letters Patent No. 374,070, dated November 29, 1887.

Application filed September 1, 1887. Serial No. 248,521. (No model.)

To all whom it may concern:

Be it known that I, THEODORE R. HOFFMAN, of Cleveland, in the county of Cuyahoga and State of Ohio, have invented certain new and useful Improvements in Paper-Fasteners; and I do hereby declare the following to be a full, clear, and exact description of the invention, such as will enable others skilled in the art to which it pertains to make and use it, reference being had to the accompanying drawings, which form part of this specification.

My invention relates to an improvement in paper-fasteners; and it consists in a fastener which is made of light sheet metal, and which has a perforated head formed upon one end, the other end being sharpened or pointed, so as to pass through the paper, and then have its end passed through the perforated head and clinched, as will be more fully described hereinafter.

The object of my invention is to provide a paper-fastener which is provided with a head or shoulders upon opposite edges, so as to form a guide to prevent the paper from tearing while being handled.

Figure 1 is a plan view of a paper-fastener embodying my invention. Fig. 2 shows the manner of fastening the heads together after the fastener has been applied to the paper.

A represents the fastener, which is made of light sheet metal; and which has a suitable opening, B, formed through one end. Upon each side of this perforation a shoulder or extension, C, extends outward at right angles to the length of the fastener for the purpose of forming a head, which, by bearing against the paper, prevents it from tearing while being handled after the fastener has been applied. From near the center of the fastener the opposite edges of the metal are cut away, so as to

form a sharp point, D, which will pass readily through the paper or through a hole which has been formed through the paper by means of any sharp instrument.

In applying the fastener to the paper either a hole is first punched through the paper or the sharp point is forced through without first cutting a hole until the two shoulders rest against the paper. The sharp-pointed end is then turned up over the edge of the paper and the perforated head is bent at right angles, so as to meet the sharp point. The point is passed through the opening in the head, and then the two parts are clinched down in the manner shown.

Where a fastener is made which has no extended shoulders upon opposite edges, the paper is not properly supported at that point where the greatest strain comes upon it while being handled, and hence is apt to break or tear. The head or shoulders form extensions which present a greater surface to the paper, and hence lessen the liability of being torn or broken.

Having thus described my invention, I claim—

A paper-fastener, A, having the two shoulders C formed on opposite sides of one of its ends, the opening B through one end, and the sharp-pointed end D, to pass through the opening B after having been forced through the paper, the shoulders serving to compress the sheets of paper together, substantially as shown.

In testimony whereof I affix my signature in presence of two witnesses.

THEODORE R. HOFFMAN.
